MOBILE DENTAL INSTRUMENT UNIT

John D. Krantz, Inglewood, Calif., assignor to Coastal Dynamics Corporation, a corporation of California

Filed Dec. 14, 1967, Ser. No. 9,788

Term of patent 14 years

(Cl. D24—1)

FIG. 1

FIG. 2

FIG. 3

FIG. 4

FIG. 5

FIG. 6

FIG. 7

FIGURE 1 is a perspective view of a mobile dental instrument unit showing my new design;

FIGURE 2 is a front elevational view thereof;

FIGURE 3 is a rear elevational view thereof;

FIGURE 4 is a left end view thereof;

FIGURE 5 is a right end view thereof;

FIGURE 6 is a top plan view thereof; and,

FIGURE 7 is a bottom plan view thereof.

The flexible tubing is fragmentarily shown in broken lines for ease of illustration.

The dominant features of my design reside in the portions shown in full lines.

I claim:

The ornamental design for a mobile dental instrument unit, substantially as shown and described.
